MOP

Frank Mullett, Toronto, Ontario, Canada, assignor of one-sixth to Mary Marguerite Cooling, London, England

Application April 15, 1936, Serial No. 74,531

1 Claim. (Cl. 15—116)

My invention relates to improvements in mops and the object of the invention is to devise a mop which will not only be efficient and not liable to get out of order but will dispense with the ordinary pail and the inconvenience of the use thereof.

A further object is to construct the mop so that all the parts are enclosed and not liable to be deleteriously affected or displaced when in use.

A still further object is to dispense entirely with the use of the hands in wringing the mop.

To effect these objects my invention consists of a suitable frame, wringing rollers journaled therein and coacting to wring the cloth, one of the rollers having the spindle thereof journaled in suitable bearings extending into hollow recesses in the frame and provided with pressure springs, a brush holder located at the bottom side of the frame and a brush held therein, all the parts being arranged and constructed in detail as hereinafter more particularly explained.

Fig. 1 is a plan view of my improved mop.

Fig. 2 is a sectional view at an angle, at which the mop is set when in use.

Fig. 3 is a perspective view showing the mop when the cloth is being utilized.

Fig. 4 is a side view showing the mop when the brush is being used.

Fig. 5 is a cross-sectional elevation when the cloth is being used.

Fig. 6 is a view looking from the top of the mop in the direction indicated by arrow, Fig. 4.

Fig. 7 is a sectional detail showing the spring pressed bearing for the upper spindle on which the upper roller is located.

Fig. 8 is a detail showing the means for the support of the spindle of the lower roller.

In the drawing like references indicate corresponding parts in the different views.

1 is the main frame of my mop which is substantially rectangular and is provided with a socket 2 for the reception of the operating handle. The frame 1 at each end is provided with recesses 3, 3 in which are located the bearings 4, 4 having the stems 5, 5, 6, 6 are spiral springs which at one end surround the stems 5, 5 and are designed to exert a pressure on the bearings 4. 7 is the spindle of the upper roller 8 which extends into the bearings 4, 4 through enlarged openings 9, 9 at each end, such openings 9 being covered by plates 10 through which the spindle 7 extends, the plates being designed to prevent dust from congregating between the ends of the rollers and the frame or entering the recesses 3.

The recesses 3, 3 are closed at their upper ends by the plates 11 which fit into dove-tailed grooves 12 in the top of the frame 1. The inner end of the plate 11 is narrow and is provided with a teat 13 which may be raised slightly by inserting the finger into the notch 14 whereupon the plate 11 may be slid outwardly when desired and removed so as to uncover the outer ends of the recesses 3 should it be desired to get at the bearings 4.

14 is the lower roller which is provided with a plurality of small projections 15 which are designed to coat with recesses 16 in the upper roller 8. The lower roller 14 is provided with a square orifice 15' extending therethrough. 16' is the spindle of the lower roller, one end of which 15 extends into the frame 1 and has a square boss 17 at the end. The spindle 16' is provided at the opposite end with a square portion 18 which is formed integral with the spindle and provided with a crank handle 19, having at the outer end 20 thereof an arm 20 provided with a handle 21. The arm 20 is pivoted at the end of the crank arm as indicated so that it may be swung, when not in use, between the clips 22 secured at the top end of the frame.

The crank arm and the spindle are preferably made in one piece and thereby any liability of the crank arm being lost is obviated. The frame 1 has an enlarged opening 23 substantially rectangular so that the spindle with the square ends may be inserted and placed in position readily. The spindle 16' and lower roller 14 are held in position by the pressure of the upper roller 8, such pressure being produced by the springs 6, see Figs. 2 and 8.

24 is the mop which extends between the rollers 8 and 14 and is preferably in the form of an endless belt, see Figs. 3 and 5, extending between the rollers and the bottom of the mop frame, which it will be seen has a row of corrugations 25 designed to grip into the mop itself and hold it in position, that is to say, not allow it to move too easily.

When the mop or mop cloth is not being used it is swung out of the way by being thrown laterally sideways from under the groove and then bunched up on top of the rollers.

It will now be seen that the lower part of the mop frame is provided with a cross-bar 26 having a dove-tailed groove. Into the groove so formed I insert a cross-bar 27 correspondingly formed to fit the dove-tail, such bar being provided with a brush 28.

The brush 28 is provided for the purpose of

rough work and scrubbing or heavy work preferably previously to the use of the mop.

Such a mop as I have described is capable of being used without the use of a pail in juxtaposition and without the necessity of having to handle the mop cloth by the hand. The freedom of the movement of the rollers is always insured and there is no liability of threads or other foreign matter being wound up in the same. In addition to this, all dust is prevented from getting into the working parts such as the springs which are protected by plates which extend over openings at the insides of the frame.

It will also be noted that the cross-bar 21 is held in position from moving laterally by means of the spring 29 indicated clearly in Fig. 2. The mop cloth is also prevented from slipping by the projections and recesses in the rollers hereinbefore referred to.

Another advantage I possess in the use of my mop is that when the brush is being used the handle and arm 20 may be swung back into position between the clips 22.

Another advantage of my mop is that the parts are very easy to assemble and everything remains in place without the use of bolts, nuts or screws. There is nothing to fall off and become lost and

no adjustment is necessary. As the mop may be used without using the hands for wringing purposes it will be seen that boiling water may be employed and the work done in a fraction of the time. There is no necessity for a woman getting down on her knees, nor is it necessary for her to do any wringing which is one of the serious objections to the use of mops at present in use. 5

Although I have described with great particularity the construction of my mop it will be understood that various changes may be made without departing from the spirit of my invention. 10

What I claim as my invention is:

The combination with a U-shaped rectangular frame having a pressure bar closing the open lower end of the frame, and a handle socket at the upper end and the side ends each having an open-ended recess and a closure therefor, of upper and lower rollers, the upper roller having spindles journalled in blocks in the recesses, springs extending between said blocks and end closures, and the lower roller having end spindles journalled in the side ends and provided with a handle, and an endless mop designed to extend between the rollers and normally guided by the pressure bar. 20 25

FRANK MULLETT.
